Attnys.

UNITED STATES PATENT OFFICE

PERCIVAL B. CROCKER, OF TAUNTON, MASSACHUSETTS, ASSIGNOR TO THE SENTRY COMPANY, OF TAUNTON, MASSACHUSETTS, A CORPORATION OF MASSACHUSETTS

POT FURNACE AND THE LIKE

Application filed May 15, 1928. Serial No. 277,893.

This invention relates to pot furnaces and similar heaters wherein a body of liquid, ordinarily molten material, is held in a suitable container readily accessible for use, as by 5 ladling out a portion thereof or by dipping an article therein. Solder pots and salt baths are instances which will readily occur to the reader. The object of the invention is to provide an improved arrangement of dis- 10 placeable cover for use with such structures.

My invention will be well understood by reference to the following description of the electrically heated pot furnace illustrated in the accompanying drawings as a single ex- 15emplary embodiment of the invention, in which drawings:

Fig. 1 is a top plan view of the furnace; and

Fig. 2 is a partial section on the line 2—2 20 of Fig. 1, with parts broken away.

In the drawings I have illustrated a furnace embodying a suitable casing 3 supporting the refractory walls 5 of a furnace chamber in which is suspended a pot or crucible 7, the open top of which is exposed at the 25 top of the furnace. The furnace shown is of the electrically heated type, as indicated by the showing of the junction box 9. In such furnaces a thermo-couple is usually in- 30 serted in the pot in order to provide for indicating or controlling the temperature of the molten material, and I have herein shown a connection for such a thermo-couple in the form of a pipe 11 leading from the junc- 35 tion box and over the top of the casing and down over the edge of the crucible (see Fig. 2). An important feature of my invention is an arrangement of parts which permits the convenient application of the thermo- 40 couple or similar device in this manner.

The form of cover illustrated comprises two semi-cylindrical lids 13 which close together along a diametral line to cover over the open top of the pot. As best seen in 45 Fig. 2, the lids 13 may embody a deeply flanged shell, the flange fitting about the top of the pot and receiving within the same a lining or filling 15 of suitable refractory and insulating materials. The two lids 13 are pivotally supported so that one or both

may be swung away, as illustrated at the left of Fig. 1, to provide access to the open top of the pot, and for this purpose they may be provided with manipulating handles 17. Ordinarily the workman would stand at one 55 side of the furnace, corresponding to the upper side of Fig. 1, and preferably both lids are pivoted at the opposite side so that they swing away from him, giving him full and convenient access to the opening. The 60 thermo-couple preferably runs in over the edge of the back side (the lower side in Fig. 1) closely adjacent the rear wall of the crucible to obstruct the same to a minimum degree. 65

Referring to Fig. 2 showing the right-hand lid, this may be pivoted on a suitable vertical axis disposed at one side of the pipe 11, and I have herein shown the semi-cylindrical shell as provided with a suitably 70 webbed arm 19 carrying a pivot 21 working in a step bearing 23 which herein takes the form of a recess in the top plate of the casing. The left-hand lid 13 may be provided with a like arm and may be similarly pivoted 75 on a separately located vertical pivot, herein directly opposite the pivot of the right-hand lid at the opposite side of the pipe 11. That is, in the embodiment of the invention shown the two lids are pivoted on vertical axes at 80 opposite sides of the diametral line which forms the joint between the closed covers and which is in alignment with the pipe 11. It will be seen that with this arrangement the pipe 11 may be led closely over the top 85 of the casing and down over the edge of the crucible 7 between the pivot bearings without interference therewith and that the lids, when closed, will fit over and above the same, they being suitably recessed, as indicated at 90 25, to receive the bend of the pipe.

To support the lids when swung back to the position of the left-hand one in Fig. 1, the top plate of the casing may be provided with suitable radiating ribs 27 which support 95 the overhung weight of the lids in the manner of tracks but permit their movement without undue friction. As is seen in Fig. 2, the pin and socket connection at 21—23 may be made a somewhat loose one in order 100

to permit a certain tilting movement of the lids transversely of the plane in which they swing. Thus a slight lifting movement of the handles will facilitate opening of the lids.

5 When opened they rest freely on the ribs 27 without strain on the pivots.

Not only are the lids displaceable but they are readily removable merely by lifting them off, if desired. The construction is simple 10 and convenient and not likely to get out of order, and possible binding of the parts is eliminated. I have already explained how the arrangement may provide for the installation of a thermo-couple or similar mechanism extending inwardly over the edge of 15 the pot.

I am aware that the invention may be embodied in other specific forms without departing from the spirit or essential attributes 20 thereof, and I therefore desire the present embodiment to be considered in all respects as illustrative and not restrictive; reference being had to the appended claims rather than to the foregoing description to indicate the 25 scope of the invention.

Claims:—

1. In a structure of the class described having a container therein opening at the top thereof, a member extending into the container over an edge thereof, a pair of lids providing a cover for the container supported to swing about separate laterally disposed vertical pivots and closing together, said lids being shaped to provide at their joint a recess to receive said member between and beneath them.

2. In a structure of the class described having a container therein opening at the top thereof, a member extending into the container over an edge thereof, a pair of lids providing a cover for the container, one of said lids being supported to swing about a vertical axis disposed laterally adjacent said member where the latter extends over said top and the other supported to swing about a separately located vertical axis, the two lids closing together to cover the container and being shaped to provide at their joint a recess receiving said member between and beneath them.

3. In a structure of the class described having a container therein opening at the top thereof, a member extending into the container over an edge thereof, a pair of lids providing a cover for the container, each having a laterally disposed pivot, step bearings at opposite sides of said member receiving said pivots swingingly to support said lids to close together, said lids being shaped to provide a recess at their joint to receive said member and closing together above and about said member.

4. In a structure of the class described having an opening in the top, a container set in the opening, a cover adapted to fit over the

top of the container comprising a pair of lids closing together thereabout, pin and socket pivots about which said lids may swing and projections on the top of the structure for supporting the said lids in open position.

5. In a structure of the class described having an opening in the top, a container set in the opening, a cover adapted to fit over the top of the container comprising a pair of lids closing together thereabout, pin and socket pivots about which said lids may swing and fitting loosely to permit tilting movement of the lids thereabout transversely of the plane in which they swing, and projections on the top of the structure for supporting the said lids in open position.

6. In a structure of the class described having a container therein opening at the top thereof, an elongated member extending into the container over an edge thereof, a cover for the container including a movable lid and a cooperating part against which said lid closes in a joint aligning with said member, said lid and part in the closed position defining a downwardly opening recess in which said member is received, said lid pivoting about a vertical axis at one side of said member.

7. In a structure of the class described having a container therein opening at the top thereof, an elongated member extending into the container over an edge thereof, a cover for the container including a movable lid and a cooperating part against which said lid closes in a joint aligning with said member, said lid and part in the closed position defining a downwardly opening recess in which said member is received, said lid having a vertical pivot working in a step bearing at one side of said member.

In testimony whereof, I have signed my name to this specification.

PERCIVAL B. CROCKER.
